UNITED STATES PATENT OFFICE.

NORMAN D. BISHOP, OF LOS ANGELES, CALIFORNIA, ASSIGNOR TO CALIFORNIA TRADING COMPANY, A CORPORATION OF CALIFORNIA.

ADJUSTABLE COMPARTMENT FOR BEDS.

1,113,871.

Specification of Letters Patent.

Patented Oct. 13, 1914.

Application filed December 18, 1913. Serial No. 807,567.

To all whom it may concern:

Be it known that I, NORMAN D. BISHOP, a citizen of the United States of America, residing at Los Angeles, county of Los Angeles, State of California, have invented a certain new and useful Adjustable Compartment for Beds; and I do hereby declare the following to be a full, clear, and exact description of the invention, such as will 10 enable others skilled in the art to which it appertains to make and use the same.

This invention relates to an adjustable compartment for a bed—more particularly to improvements of the compartment for a bed 15 disclosed in Patent No. 1,063,908, dated June 3, 1913—and it may be said to consist in the provision of the novel and advantageous features and in the improved construction, arrangement, and combination of parts and 20 devices as will be apparent from the description and claims which follow hereinafter.

It has been found in practice that the pivoted arc-shaped plate or canopy described in the above patent is objectionable 25 in that it is comparatively difficult and expensive to manufacture, practically impossible to make it tight and wind proof, requires heavy counterweights, collects dust and moisture when it is disposed on the out- 30 side of the building and carries such dust or moisture into the room of the building when it is swung to be disposed on the inside of the building, does not permit of completely opening the bed compartment at 35 both the front and rear to enjoy cooling drafts of air in warm weather, shuts in and prevents the wants of young children occupying the bed from being readily known when it is swung to be disposed on the in- 40 side of the building, must be swung to the outside of the building in inclement weather or else the curtain must be pulled down which curtain in consequence of exposure to the elements is caused to shrink and rot and 45 must soon be replaced at considerable expense, and it mars the appearance of the building because its curved portion does not comport with the architectural lines of the exterior of the building.

50 Objects of the invention are to provide an improved bed compartment which avoids the foregoing objections, and which is simple and economical in construction, strong and durable, neat in appearance, readily

and quickly adjusted, convenient and effective in use, designed to allow more head room for those occupying the bed, made of comparatively few parts which fit together without the necessity of great accuracy in the work, light in weight and easily knocked 60 down to permit of shipment at a low cost, and which can be placed on the market at a comparatively low price.

Other objects and the advantages of the invention will be apparent to those skilled 65 in the art from a consideration of the following description of forms of construction embodying the invention, taken in connection with the accompanying drawings in which—

Figure 1 is a broken sectional view of a bed compartment embodying the invention; Fig. 2 is a broken sectional view taken on the line 2—2 of Fig. 1; Fig. 3 is a broken sectional view of a modified construction for 75 the bed compartment; Fig. 4 is a broken sectional view of another construction for the bed compartment; Fig. 5 is a fragmentary sectional view of another modified construction for the bed compartment; Fig. 6 80 is a broken sectional view taken on the line 6—6 of Fig. 5 and showing the side walls; Fig. 7 is a broken sectional view of the bed compartment taken on the line 7—7 of Fig. 1; with parts in changed position; Fig. 8 is 85 an enlarged broken sectional view taken on the line 8—8 of Fig. 3; Fig. 9 is a sectional view taken on the line 9—9 of Fig. 8, showing the spring-operated roller; Fig. 10 is an enlarged broken sectional view of parts 90 shown in Figs. 1 and 3 in changed position; and Fig. 11 is an enlarged broken sectional view of a portion of the construction shown in Fig. 4.

In the several views similar parts are des- 95 ignated by like reference characters.

The compartment is designed to receive therein any suitable or approved form of bed 12, and in use is adapted to be arranged on a floor 13 of a building having a suitable opening in the wall 14 thereof through which the compartment extends to have its rear portion disposed on the exterior of the building and its front portion disposed on the interior of the building.

As shown, the compartment has at its sides frames or uprights 15 and 16 to which are suitably secured inner walls 17 and pref-

70

105

erably also outer walls 18. At the top of the side walls 17 and 18 is disposed a crosspiece 19 to which or to a molding 20 at the front thereof is connected the hinged sections 21 and 22 of the back of a seat or other suitable means for closing the front portion of the compartment. When as shown in this instance the front portion of the compartment, which is disposed on the interior of the building, is in the form of a seat, the front end of the seat may consist of the hinged sections 23 and 24 to which are connected hinged sections 25 and 26 which are adapted to form the horizontal portion of the seat; also the sections 23 and 25 may be mechanically connected with the bed 12 as disclosed in my Patent 1,063,909, dated June 3, 1913. As shown in Fig. 1, the section 22 of the back portion of the seat may have thereon a knuckle plate 27 to which is pivotally connected one end of a link 28 which has its other end pivotally connected to one end of a link 29 which latter is mounted on a pivot 30 and has its other end suitably connected to springs 31 which are suitably attached to the walls 17 or 18, whereby the sections 21 and 22 are counterbalanced and held in raised position when it is desired to open the front portion of the compartment.

In the construction of the compartment shown in Figs. 1, 2, and 7, the rear portion of the compartment which is disposed on the exterior of the building comprises a substantially vertical stationary end wall 32 which extend between the side walls of the compartment and may have thereon a top piece 33 having therein a groove into which is adapted to fit one end of an adjustably movable cover consisting of sections 34 and 35 which are connected together by hinges 36 and connected to the crosspiece 19 by hinges 37. The section 34 has thereon rollers 38 adapted to travel in guideways 39 on the walls 17, and the section 35 has thereon a knuckle plate 40 to which is pivotally connected one end of a link 41 which latter has its other end pivotally connected to one of the arms of a bell crank 42 fast on the shaft 43 bearing in the walls 17 and 18. The other arm of the bell crank 42 is pivotally connected to a link 44 which is suitably attached to springs 45 which are suitably attached to the walls 17 or 18. By swinging the lever 46 which is secured to the shaft 43, the shaft 43 is turned and the bell crank 42 and link 41 act to raise the hinged sections 34 and 35 to effect the desired amount of opening in the rear portion of the compartment which is disposed on the exterior of the building. The springs 45 act to counter-balance the hinged sections 34 and 35 and hold them in the raised position shown in dotted lines in Fig. 1. A gutter 47 is preferably disposed across the top of the compartment at

the junction of the section 35 with the crosspiece 19 to prevent leakage of water onto the bed 12.

The gutter 47 preferably consists of a curved strip of spring metal which has one of its ends suitably affixed to a spring metal tongue 48 which is suitably secured to the section 35 and has its other end adapted to bear movably against an abutment 49 on the crosspiece 19.

A curtain 50 mounted on the usual spring-actuated roller 51 bearing in the walls 17 is adapted to close the front portion of the compartment when the sections 21, 22, 24, 25 and 26 have been adjusted to open said front portion of the compartment. The curtain 50 is preferably secured by a rigid strip 52 to sector plates 53 which are mounted on pivots 54 on the walls 17 and have thereon pins 55 adapted to fit in eyes 56 in the sides of the curtain, so that the sector plates may be turned by a handle 57 to draw the curtain evenly and tightly over the arc-shaped periphery of the sector plates to close the front portion of the compartment, see Figs. 1 and 7.

In the modified construction shown in Figs. 3 and 4 of the rear portion of the compartment which is disposed on the exterior of the building, the sections 58 are movably fitted in guideways 59 in the walls 17 and 18 and adapted to be moved to occupy a position behind the vertical stationary wall 32 at the rear end of the compartment. Any suitable or approved means may be used to hold the section 58 in adjusted position, that shown in Figs. 8 and 9 consisting of a spring-actuated roller 60 which is suitably mounted at the upper part of the walls 17 and 18 and has attached thereto one end of a metal tape 61 which latter has the other end thereof suitably attached to the upper part of the section 58. In Fig. 3, the hinged sections 62 and 63 which are adapted to fit over the top of the walls 17 and 18 and are hinged to the crosspiece 19, may be adjusted and held in raised position by means operatively connected with the section 63 such as that which has been described as operatively connected to the section 35 in Fig. 1. In Fig. 4, the overlapping sections 64, 65, and 66 are slidably mounted on the top of the walls 17 and 18, and the section 64 is suitably connected with a chain 67 which passes around sprocket wheels 68 and 69 suitably arranged between the walls 17 and 18 so that when the sprocket wheel 69 is turned by a handle 70 connected therewith, the section 64 is moved under the section 65 to have the projection 71 engage the rear end of the section 65 whereupon the sections 64 and 65 are moved under the section 66 until the projection 72 engages the rear end of the section 66 whereupon the sections 64, 65, and 66 are moved under the crosspiece 19 until the projection 73

73 engages the rear end of the crosspiece 19. The sections 64 and 65 have thereon projections 72' and 73' which engage with and move the sections 65 and 66 when the handle 5 70 is turned in the opposite direction to close the rear portion of the compartment.

In the modification of the construction of the rear portion of the compartment shown in Figs. 5 and 6, the hinged together sections

10 74 have the side portions thereof movably bearing against guides 75 on the walls 17 and have one end thereof suitably connected to the roller 76 which is rotatably mounted on the walls 17 and have the other end 15 thereof extending to the floor 13 to close the rear portion of the compartment. The roller 76 may have thereon a bevel pinion 77 in mesh with a bevel pinion 78 on the upper end of an upright shaft 79 which latter has 20 on its lower end a bevel pinion 80 in mesh with a bevel pinion 81 to which is connected a handle 82. When the handle 82 is turned in the direction indicated by the arrows the roller 76 is turned to wind up the hinged 25 together sections 74 and thereby open the rear portion of the compartment which is disposed on the exterior of the building. Covering plates 83 are preferably secured to the walls 18 and adapted to overhang the 30 side portions of the sections 74.

It will be seen that the improved bed compartment is comparatively simple in construction and is well adapted to accomplish the objects of the invention.

35 Though various forms of construction embodying the invention have been illustrated and described, many changes and modifications thereof will occur to those skilled in the art—wherefore the right is reserved to 40 all such changes and modifications as do not depart substantially from the spirit and scope of the invention as defined in the appended claims.

I claim:

45 1. A compartment for a bed adapted to extend through an opening in the wall of a building, comprising side walls, suitable adjustable means in the form of a seat for closing the front portion of the compartment which is disposed in the interior 50 of the building, adjustable means including relatively movable sections for closing the rear portion of the compartment which is

disposed on the exterior of the building, means operatively connected with the sections for moving the same to open the rear portion of the compartment, sector plates pivotally mounted on the side walls, a roller curtain mounted on the side walls and provided with eyelets, and pins on the sector plates adapted to fit in said eyelets as set forth.

2. A compartment for a bed having side walls, adjustable means including relatively movable sections placed on the side walls 55 for closing the rear portion of the compartment, and means for closing the front portion of the compartment, including sector plates pivotally mounted on the side walls, a spring actuated roller mounted on the side 60 walls, a curtain provided with eyelets and having one end thereof secured to the roller, and having the other end thereof secured to the sector plates, and pins on the sector plates adapted to fit in the eyelets when the 65 sector plates are turned as set forth.

3. In a compartment for a bed, the combination of side walls, means including relatively movable sections on the side walls at the rear of the compartment, means operatively connected with said sections for moving the same to open the rear portion of the compartment, sector plates pivotally mounted on the side walls, a roller curtain mounted on the side walls and provided with eyelets, and pins on the sector plates adapted 80 to fit in said eyelets as set forth.

4. A compartment for a bed having side walls, means including relatively movable sections placed on the side walls for closing 90 the rear portion of the compartment, sector plates mounted on the side walls, a spring actuated roller mounted on the side walls, a curtain on the roller for closing the front portion of the compartment, eyelets in the 95 curtain, and pins on the sectors adapted to fit in said eyelets as set forth.

In testimony whereof, I have signed my name to this specification in the presence of two subscribing witnesses at Los Angeles, 100 county of Los Angeles, State of California, this 9th day of December A. D. 1913.

NORMAN D. BISHOP.
